DESIGN FOR AN EXPANSIBLE LINK CHAIN FOR A BRACELET OR SIMILAR ARTICLE

Emil E. Fachon, Edgewood, R. I., assignor to
Bulova Watch Company, Inc., New York, N. Y.,
a corporation of New York

Application June 28, 1947, Serial No. 139,996

Term of patent 7 years

(Cl. D45—4)

To all whom it may concern:

Be it known that Emil E. Fachon, a citizen of the United States of America, residing at 12A Sefton Drive, Edgewood, Rhode Island, in the county of Providence and State of Rhode Island, has invented a new, original, and ornamental Design for an Expansible Link Chain for a Bracelet or Similar Article, of which the following is a specification, reference being had to the accompanying drawing, forming part thereof.

Fig. 1 is a top plan view of an expansible link chain showing my new design;

Fig. 2 is an end view looking in the direction of the arrows 2—2 of Fig. 1;

Fig. 3 is an edge elevational view of the link chain;

Fig. 4 is a bottom plan view thereof; and
Fig. 5 is a top plan view of the link chain in an expanded position.

I claim:

The ornamental design for an expansible link chain for a bracelet or similar article, as shown.

EMIL E. FACHON.
